UNITED STATES PATENT OFFICE.

RICHARD B. BILLINGS AND JAMES EDWARD O'TOOLE, OF UTICA, NEW YORK.

CABLE PULLER.

Application filed June 6, 1927. Serial No. 203,827.

This invention relates to a cable puller of the type adapted to be readily attached to and detached from cables or wires even where a free end of the cable or wire is not available.

The purpose of our invention is to provide a cable puller of the type described of new and improved construction and one which is simple but reliable in operation.

10 A further purpose is to provide a cable puller of the type mentioned of such construction, combination and cooperation of its parts as will enable the device to be safely used even where a tension of many thousand pounds has to be placed upon the cable being drawn tight by the cable puller. Due to the leverage used in the tool to grip the cable for such a pull much greater strain is placed upon some parts of the tool than 20 upon the cable and it is the purpose of our invention to provide what may be called a heavy duty puller that will stand the strain of such use without injuring the cable and without breaking, straining or 25 distorting the tool.

Another purpose is to provide a heavy duty cable puller which can be satisfactorily and readily used without change or adjustment of its parts upon cables of more than 30 one diameter.

Further purposes and objects of our invention will appear from the specification and claims herein.

Fig. 1 is a plan view of a cable puller 35 embodying our invention with the jaws and cam levers shown in extended or open position.

Fig. 2 is a plan view of the near or front side of the tool shown in Fig. 1.

40 Fig. 3 is a plan view of the device shown in Fig. 1 with the jaws closed and engaging a section of cable but with the retracting arms removed in order to more closely show certain other details of construction.

45 Fig. 4 is a vertical sectional view on line 4-4 of Fig. 3. Fig. 5 is a plan view of the connecting link. Fig. 6 is a plan view of one of the retracting arms.

Referring to the drawings in a more particular description it will be seen that the device comprises a connecting link 10, a pair of generally similar jaws 11-11 and a pair of similar cam levers 12-12.

The connecting link 10 is a relatively 55 wide, heavy member constructed of material

well adapted to stand the strain to be placed thereupon. It is provided at its opposite ends with a vertically disposed hole 13 through which extends the pivot pin 14 connecting each end of the link to the forked 60 ends 15 and 16 of the cam lever 12.

The jaws 11-11 are provided intermediate their length and intermediate their vertical height with a transverse slot 17 the width and especially the height of which is 65 a little greater than the width and height respectively of the link 10. This excess of height in the slots over the height or thickness of the link allows the jaws to swing a slight amount either way from a position 70 at right angles to the lengthwise plane of the link so that the tool may be applied to several varying sizes of cable or wire without putting a twisting or bending strain upon the link.

The jaws 11 are of considerable length say about three times the width of the connecting link 10 and in the opposing faces 17 of the jaws to one side of the link 10 there is provided in each jaw a longitudinally extending cable-engaging groove 18. These grooves are concave of a curvature to adapt the jaws to engage a cable or wire of the size for which the tool is adapted around a considerable surface of the cable so as to 80 increase the area of the surface engaged by the tool and prevent distortion or marring of the cable.

As the tool is illustrated in the drawings 85 these cable-engaging grooves 18 are shown of these grooves and of the cable below the link 10 but it will be obvious that when desired the tool may be applied bodily from the lower side of the cable and so bring the tool in a position reverse to that shown in 90 the drawings. In other words, the location of these grooves and of the cable below the link is simply for the purpose of definiteness in describing the tool. Preferably the 95 opposing faces of the jaws are so shaped as to have the lip 19 below the groove 18 cut away or formed back from the general plane of the opposing faces 17 and also rounded as shown on their lower sides as at 20 in order to more readily allow the tool to be applied 100 to the cable and so that the relatively short range of movement of the jaws towards each other will more quickly and effectively obtain a gripping contact upon the cable.

To the other side of the link 10, that is to 110

the top of said link as the parts are shown in Figs. 1 to 4 of the drawings the right hand jaw is provided with a projecting ridge 21 extending the length of said jaw and rounded or curved at its outer part forming a face 22 to engage the opposing surface of the left hand jaw which opposing surface is preferably provided with a longitudinally concave groove 23 allowing a rocking or rolling engagement between said ridge 21 and groove 23 when the jaws of the tool are brought together. An examination of Figs. 2 and 4 of the drawings especially will show that when the jaws are brought together upon a cable of any one of the sizes for which the tool is adapted the cable will be gripped between the two grooves 18 to one side of the link and ridge 21 at the other side of the link will engage the opposing surface of the left hand jaw along the groove 23. It will be understood that the ridge 21 and other parts of the tool are so proportioned that when the tool is applied to a cable of the average size for which it is adapted to be used the vertical plane of the two jaws will be maintained in position about as shown in Figs. 2 and 4. When the tool is applied to a larger sized cable the jaws even when closed upon the cable will rock to slightly divergent planes with the upper engaging surfaces of the two jaws forming the fulcrum point for the said jaws. When the tool is applied to a cable of a smaller size within the range allowed, the two jaws will rock upon these same faces 22 and 23 as fulcrum points but with the lower parts of the jaws somewhat closer together than shown in Fig. 4. It will be seen that in any of these three positions the pressure communicated to the jaws by the cam faces 24 of the cam levers 12 is transmitted to the cable without placing a bending strain upon the link 10.

The inner ends of the cam levers 12 are forked as most plainly shown in Fig. 2 and through the two forked ends of each lever extends the pivot pin 14 for said lever. Upon both the upper and lower forks of each lever are provided the cam faces 24. These cam faces are farther from the axis of the pivot pin 14 towards the front of the forks as the forks are seen in Fig. 2 so that as the cam levers 12 have their outer ends drawn forward relative to the jaws the said jaws will be forced together in an obvious manner with great power upon the cable to be gripped thereby. Preferably the part of the outer sides 25 of the two jaws where said sides are to engage the cam faces 24 will be curved inwardly forming a cam-engaging way 26. These cam-ways 26 are concave following as close as practicable to the curve of the cam faces 24 so that the pressure transmitted to the jaws from the cam faces will be distributed over an appreciable surface and not to a line as would be the case

if the cam-way was left flat. In this way wear of the parts is largely avoided and the life of the tool is prolonged.

Means are provided to automatically and positively retract the jaws to open position by the moving of the cam levers back to open, that is extended position.

These means comprise an arm 27 secured to each jaw and projecting outwardly past the outer side 25 of the jaw and there provided with a depending finger 28 which engages the eccentric curved shoulder 29 on the jaw side of a recess 30 conveniently circular formed in the top of the upper forked end of the cam lever 12. The position of the two fingers 28 is indicated in dotted lines in Fig. 3 and it will be obvious that upon the cam levers being swung back to open position the pins riding along the shoulder 29 will be drawn back closer to the axis of the pivot pins 14 and so will draw the jaws away from each other to the position of the parts shown in Fig. 1. For convenience in manufacturing the device these retracting arms 27 will preferably be formed as separate parts from the jaws but readily and rigidly secured thereto by means of screws 31 extending through the arms into the jaws. The portion of the arms over the jaws may be countersunk more or less into the upper surface of the jaws.

Suitable means such as a long clevis or draw bar or loop 31 is pivotally connected to the outer end of each cam lever for connecting the tool to the hook of the tackle-block or other source of power.

Under certain working conditions it is an advantage to have the tool automatically grip the cable with a moderate pressure as soon as the cable and tool are brought together and without waiting for the drawing power to be applied to the cam levers. To accomplish this we provide the tool with a tension spring 32 having its ends connected (preferably detachably) to the cam levers. The tension and length of the spring are such as to normally yieldingly draw the levers more or less to the closed position and the tension of the spring upon the levers is sufficient to hold the tool in place upon the cable. When the tool equipped with such a spring is to be applied to a cable the levers are temporarily straightened or opened out against the tension of the spring. When this feature is not desired the spring is readily detached from the tool.

What we claim as new and desire to secure by Letters Patent is:

1. In a cable puller the combination of a connecting link, a pair of jaws slidably mounted intermediate their ends on said link and each having a cable-engaging surface to one side of said link and having at the other side of said link a co-operating face which faces are adapted to meet each

other and form fulcrum faces when a cable is engaged by the tool and cam levers pivoted to the opposite ends of said link and having cams engaging the adjacent jaw and operating to move the jaws together as the outer ends of the levers are drawn forward.

2. In a cable puller the combination of a connecting link, a pair of jaws slidably mounted intermediate their ends on said link and each having a cable-engaging groove to one side of said link and having at the other side of said link a co-operating face which faces are adapted to meet each other and form fulcrum faces when a cable is engaged by the tool and cam levers pivoted to the opposite ends of said link and having cams engaging the adjacent jaw and operating to move the jaws together as the outer ends of the levers are drawn forward.

3. In a cable puller the combination of a connecting link, a pair of jaws slidably mounted intermediate their ends on said link and each having a cable-engaging surface to one side of said link and having at the other side of said link a co-operating rocking face, which faces are adapted to meet each other and form fulcrum faces when a cable is engaged by the tool and cam levers pivoted to the opposite ends of said link and having cams engaging the adjacent jaw and operating to move the jaws together as the outer ends of the levers are drawn forward.

4. In a cable puller the combination of a connecting link, a pair of jaws slidably mounted intermediate their ends on said link and each having a cable-engaging groove to one side of said link and having at the other side of said link a co-operating rocking face, which faces are adapted to meet each other and form fulcrum faces when a cable is engaged by the tool, and cam levers pivoted to the opposite ends of said link and having cams engaging the adjacent jaw and operating to move the jaws together as the outer ends of the levers are drawn forward.

5. In a cable puller the combination of a connecting link, a pair of jaws slidably

mounted intermediate their ends on said link and each having a cable-engaging groove to one side of said link and having at the other side of said link a co-operating rocking face, which faces are adapted to meet each other and form fulcrum faces when a cable is engaged by the tool, cam levers pivoted to the opposite ends of said link and having cams engaging the adjacent jaw and operating to move the jaws together as the outer ends of the levers are drawn forward.

6. In a cable puller the combination of a connecting link, a pair of jaws slidably mounted intermediate their ends on said link and each having a cable-engaging groove to one side of said link and having at the other side of said link a co-operating face, which faces are adapted to meet each other and form fulcrum faces when a cable is engaged by the tool and each having on its outer side a curved cam-engaging way and cam levers pivoted to the opposite ends of said link and having cams engaging the cam way on the adjacent jaw and operating to move the jaws together as the outer ends of the levers are drawn forward.

7. In a cable puller the combination of a connecting link, a pair of jaws slidably mounted intermediate their ends on said link and each having a cable-engaging groove to one side of said link and having at the other side of said link a co-operating face which faces are adapted to meet each other and form fulcrum faces when a cable is engaged by the tool, cam levers pivoted to the opposite ends of said link and having cams engaging the adjacent jaw and operating to move the jaws together as the outer ends of the levers are drawn forward, and yielding tension means operatively connected to yieldingly draw the jaws together.

In witness whereof we have affixed our signatures, this 28th day of June, 1927.

RICHARD B. BILLINGS.
